3 SHEETS-SHEET 3.

UNITED STATES PATENT OFFICE.

JOHN G. WILLICH, OF ELM CREEK, NEBRASKA, ASSIGNOR OF ONE-FOURTH TO CHARLES STEELE, OF ELM CREEK, NEBRASKA.

ATTACHMENT FOR CASH-REGISTERS.

1,081,478.

Specification of Letters Patent. Patented Dec. 16, 1913.

Application filed September 9, 1912. Serial No. 719,415.

To all whom it may concern:

Be it known that I, JOHN G. WILLICH, a citizen of the United States, residing at Elm Creek, in the county of Buffalo and State of Nebraska, have invented a new and useful Attachment for Cash-Registers, of which the following is a specification.

The device herein disclosed is a change making machine, adapted to be assembled 10 with a cash register, to the end that when a purchase is rung up on the cash register, the correct change will be delivered, a portion of the mechanism of the money changing device coöoperating with a movable member 15 of the cash register to effect the result above mentioned.

The invention aims to provide novel mechanism whereby a plurality of change receptacles may be selectively actuated to hold 20 back and to deliver the coin, thereby depositing the required change.

With the above and other objects in view which will appear as the description proceeds, the invention resides in the combination 25 and arrangement of parts and in the details of construction hereinafter described and claimed, it being understood that changes in the precise embodiment of invention herein disclosed can be made within the 30 scope of what is claimed without departing from the spirit of the invention.

In the drawings, Figure 1 shows the invention in vertical transverse section assembled with a cash register; Fig. 2 is an elevation of the device herein disclosed, detached from the cash register; Fig. 3 is a top plan of the structure shown in Fig. 2; Fig. 4 is a transverse section taken adjacent 40 one end of the device; Fig. 5 is a fragmental elevation of a part of the mechanism whereby the depositing of a nickel is controlled; Fig. 6 is a side elevation showing a portion 45 of the mechanism whereby the structure shown in Fig. 6 is actuated; Fig. 7 is perspective showing one of the actuating plungers and attendant parts; Fig. 8 is a sectional elevation showing the coöperation between the no-change plunger and attendant parts; and Figs. 9, 10, 11 and 12 are plans 50 of certain actuating plates which enter into the operation of the structure.

In carrying out the invention there is provided a case equipped along its sides with

horizontally disposed guides 2 supporting a platform 3 which is located at the rear of the case 1. Secured to a cross bar 4 and united by braces 4^a, or upheld in any other desired manner in the case 1, above the platform 3 are a plurality of receptacles denoted by the numerals 5, 6, 7, 8, 9, 10, 11, 12 and 14. The receptacle 5 is adapted to contain nickels, the receptacles 6 and 7 are adapted to contain dimes, quarters are contained in the receptacle 8, fifty cent pieces are contained in the receptacle 9, the receptacles 10, 11 and 12 hold dollars, and the receptacle 14 is a five dollar receptacle. It will be understood, however, that the receptacles may be of a shape to accommodate any desired medium of exchange.

Supported upon the platform 3 and extended from the back of the case 1 toward the front thereof are a plurality of guides 15, containing slides 16 which move horizontally between the lower ends of the several receptacles and the platform 3. In each slide 16 there is an opening 17 adapted to be alined with an opening 18 fashioned in the platform 3, each opening 18 being directly beneath one of the receptacles 5—14. 75 Springs 19 are connected with the slides 16 and with the guides 15, or with any other portion of the case 1, the springs 19 serving to retract the slides 16 so that the openings 17 and 18 are out of alinement, the several 80 slides 16 normally closing the lower ends of the receptacles 5—14. The slides 16, however, may be drawn forwardly to aline the openings 17 and 18, whereupon the contents of the receptacles 5—14 will fall upon 85 and ride along a downwardly and forwardly inclined chute 20, the coins ultimately coming to rest in a pocket 20^a formed at the forward edge of the chute 20 and adjacent the front of the cash register 55 wherewith the 90 case 1 may be assembled.

Mounted to slide upon the guides 2 are supports 21, normally retracted into engagement with the forward edge of the platform 3 by means of springs 22. Mounted 100 in the supports 21 and extended transversely of the case 1 is a primary shaft 23 upon which are fulcrumed intermediate their ends, a plurality of latches 24, there being one latch 24 for each of the slides 16. At their 105 rear ends, the latches 24 are provided with

hooks 25, adapted to engage in openings 25^a in the slides 16. A plurality of tappets 26 are provided, there being one tappet for each latch 24, the tappets being located above the latches. The tappets are mounted to slide in a secondary shaft 27 which is journaled in the supports 21, and in a supplemental shaft 28 which is journaled in the case 1 as shown at 29. The tappets 26 are normally uplifted, each, by means of a spring 26^a, connected with the supplemental shaft 28.

Extended transversely of the case 1 and terminally supported therein is a rod 30 upon which are fulcrumed a plurality of levers 31, there being one lever 31 for each of the tappets 26. Connected with the levers 31 are plungers 32, 33, 34, 35, 36, 37 and 38. The plunger 32 coöperates with the five cent receptacle 5, the plunger 33 coöperates with the dime receptacle 6, the plunger 34 coöperating with the twenty-five cent receptacle 8, the plunger 35 coöperating with the fifty-cent receptacle 9 and the plunger 36 coöperating with the one dollar receptacle 10. The plunger 37 is provided with a lateral arm 39 coöperating with the lever 31 of the one dollar receptacle 11, the plunger 37 being adapted to control change to the amount of two dollars. The plunger 38 coöperates with the receptacle 14 which, in the present instance, is a five dollar receptacle.

Attention is now directed to Fig. 7, the same being compared with Fig. 3, wherein it will be seen that each of the levers 31 is equipped with a finger 40 which extends to the left, and with a finger 41 which extends to the right. The finger 40 of one lever 31 overlaps the finger 41 of the next lever to the left, the construction being such that when any one lever 31 is depressed, all of the other levers to the left will be depressed through the coöperation of the fingers 40 and 41.

Secured to the end walls of the case 1 adjacent the front of the case are guides 42 provided with a plurality of slots 43. Bars 44 extend transversely of the case 1, the ends 50 of the bars 44 being received slidably in the slots 43 of the guides 42. A plurality of cards or plates are provided, these cards or plates being designated generally by the reference character 45. Several specific plates are shown in Figs. 9, 10, 11 and 12. The several plates, denoted specifically by the numerals 46, 47, 48 and 49 are illustrative merely, and the plates may be shaped variously, the plates being provided with slots 50 located as may be desired. The bars 44 pass through the slots 50 of the several plates. When one of the plates 45 is actuated, the plate may move independently of the bars which pass therethrough, but when a bar 44 is lifted, the said bar will pick up

and elevate a plurality of the plates, the function of the operation above described being rendered evident hereinafter. Depending arms 51 located at the front of the case 1 are connected to certain of the cards or plates 45, other depending arms 52, similarly located, being connected to the bars 44. All of the arms 51 and 52 are provided at their lower ends with projecting fingers 53, adapted to be engaged by the inner ends 75 of the key levers 54 of the cash register 55, the buttons of the levers 54 being indicated at 56.

A shaft 57 extends transversely of the case 1 and is journaled in the end walls of the case, the shaft 57 being terminally provided with a handle 58. Intermediate its ends, the shaft 57 is equipped with cranks 59 connected by links 60 with the supports 21.

Mounted upon the supports 21 is a fulcrum rod 61 upon which a plurality of latches 62 are mounted for individual swinging movement, there being one latch for each tappet 26. Terminally secured in the case 1 is a rod 63 which, under circumstances to be pointed out hereinafter, is adapted to engage with the forward ends of the latches 62. The rear ends of the latches 62 are engaged with shoulders 64 formed upon the tappets 26.

Pivots connected with the cards or plates 45, as shown at 66, are levers 65, the same being fulcrumed intermediate their ends upon a rod 67 which extends across the case 1. There is one lever 65 for each of the tappets 26, and each lever 65 at its rear end is adapted to bear upon a pin 68 which projects laterally from the tappet 26.

Referring to Fig. 4 and comparing the same with Figs. 2 and 3, it will be seen that an actuating mechanism peculiar to the nickel plunger 32 and attendant parts is provided. This mechanism includes a lever 70 pivotally supported as indicated at 69, upon one end of the case 1, the lever 70 being provided at its outer end with a depending arm 71, the arm 71 corresponding to the arms 51 and 52 and being provided at its lower end with a projecting finger 72, adapted to be engaged by one of the levers 54 of the cash register. The forward end of the lever 70 is thrust upwardly through the medium of a spring 78. An arm 73 is pivoted as indicated at 74 to the inner end of the lever 70 for movement only in the plane in which the lever swings. Pivotally connected with the arm 73 is a pawl 75 which is mounted to swing transversely of the plane in which the lever 70 swings. The numeral 76 indicates a lever peculiar to the plunger 32, the function of the lever 76 being the same as the functions of the levers 31 hereinbefore described. Both the lever 76 and the lower end of the pawl 75 rest

upon the upper end of the tappet 26 which is peculiar to the nickel plunger 32. The lower end of pawl 75 is maintained above the end of the tappet 26 of the nickel plunger by means of a spring 77 which is connected with the arm 73 and with the pawl 75. The pawl 75 moves within a guide 78' which is secured to one end of the case 1. A bracket 80 projects at one end of the case 1 and upon the bracket 80 is journaled a pinion 81 having a projecting pin 81^a which is adapted to engage the pawl 75 and to swing the pawl out of vertically alined relation with respect to the tappet 26 which is peculiar to the plunger 32. The plunger 33, which is the dime plunger, is equipped with a rack bar 82 which meshes into the pinion 81.

In addition to the above mentioned plungers, there is provided a vertical plunger 83, hereinafter referred to as the "no-change" plunger, the plunger 83 having a laterally projecting arm 84 which engages across the lever 76 of the nickel mechanism.

The operation of the structure hereinbefore described is as follows: Suppose that a twenty-five cent purchase has been made, a dollar having been tendered in payment. The proper button 56 of the cash register 55 is pressed to actuate the corresponding lever 54 and to ring up the twenty-five cent purchase upon the register 55. When the lever 54 of the register 55 is actuated, the lever 54, engaging the finger 53 of one arm 51 will raise the arm 51, the arm 51 raising the corresponding plate 45. When the plate 45 is lifted, the attached lever 65 will tilt upon the fulcrum rod 67, the inner end of the lever 65 striking the pin 68 on the tappet 26, the tappet 26 being depressed and the spring 26^a being put under tension. When the tappet 26 is moved downwardly, the latch 62 which is engaged with the shoulder 64 on the tappet is tilted. When the tappet 26 is depressed, the lower end of the tappet will strike one end of the latch 24 and swing the latch on the shaft 23 so that the hook 25 of the latch is out of engagement with the opening 25^a in the particular slide 16 which coöperates beneath the twenty-five cent receptacle. This slide 16 is therefore left in such a position that the opening 17 therein is out of alinement with the receptacle 8 and out of alinement with the opening 18 in the platform 3. Consequently none of the coins in the twenty-five cent receptacle 8 can pass into the chute 20. Recalling that one dollar has been tendered against a twenty-five cent purchase, the one dollar plunger 36 is depressed. When the plunger 36 is depressed, the corresponding lever 31 is swung upon the fulcrum rod 30. The left hand finger 40 of the lever 31 will actuate the right hand finger 41 of the next lever

31 to the left, all of the fingers thus coacting to the left hand end of the machine, and when the levers 31 are actuated, all of the tappets 26 to the left of the one dollar tappet will be depressed along with the one dollar tappet. All of the latches 24 to the left of the one dollar latch will be tilted out of engagement with the respective slides 16, so that all of the slides to the left of the one dollar slide together with the one dollar slide, may remain beneath the respective receptacles 10, 11, 12 and 14. By the original operation, beginning with the actuation of the cash register lever 54, the slide 16 which is beneath the twenty-five cent receptacle 8 has been unhooked from the corresponding latch 24, and by the action of the plunger 36 and associated parts, those slides 16 which lie beneath the receptacles 10, 11, 12 and 14 are unlocked from the respective latches 24. The only slides 16 which are now subject to withdrawal by the latches 24 are those slides which lie beneath the fifty-cent receptacle 9, beneath the two ten-cent receptacles 6 and 7 and beneath the five-cent receptacle 5. It will therefore be seen that when the slides which are beneath the receptacles 9, 6, 7 and 5 are withdrawn, seventy-five cents, the correct change from a dollar tendered against a twenty-five cent purchase, will be discharged upon the chute 20 and it will pass into the pocket 20^a.

The operation of withdrawing the slides 16 from beneath the receptacles 9, 6, 7 and 5 is as follows: Rotation is imparted to the shaft 57 by the handle 58, whereupon the cranks 59 will actuate the links 60, the links 60 drawing the supports 21 forwardly upon the guides 2, the springs 22 being put under tension. When the supports 21, are moved forwardly, the forward ends of the latches 62 will ride on the rod 63, the rear ends of the latches 62 being held in engagement with the shoulders 64 of the tappets 26 which have been operated to tilt certain latches 24 out of engagement with those slides which are to remain beneath the receptacles from which no change is to be discharged. When the supports 21 are thus drawn forwardly, the primary shaft 23 will move forwardly together with those latches 24 which are engaged with the slides 16 of the receptacles 9, 6, 7 and 5, and these slides will be withdrawn, change to the amount of seventy-five cents being thus discharged into the chute 20. When the supports 21 are slid, the rotatably mounted shafts 27 and 28 will permit the tappets 26 to have the necessary swinging movement. When the handle 58 of the shaft 57 is released, the springs 22 will retract the supports 21 into abutment with the platform 3, and the latches 62 will ride off the rod 63, effecting a release of the tappets 26 which have been

held down to tilt certain of the latches 24 out of engagement with the corresponding slides 16.

In the foregoing description, it has been presupposed that an arm 51 which is attached to one plate 45 has been actuated; but one of the levers 54 of the cash register may have engaged with an arm 52 which is attached to one of the bars 44, depending upon the amount of purchase which has been rung up upon the cash register. When one of the bars 44 is thus actuated, the bar, engaging in the slots 50 of the plates 45 will pick up a series of plates and operate several plates and attached mechanism in the manner hereinbefore described. The plates or cards 45 may be slotted in a variety of ways to enable them to be picked up by one or more of the bars 44, and thus an almost endless variety of combinations may be made, permitting an unlocking of the proper coin slides 16 to represent the amount of purchase rung up on the cash register. When the no-change plunger 83 is depressed, its arm 84 will actuate the lever 76 of the first or five-cent plunger 32 and the several fingers 40 and 41 will interengage to depress all of the tappets 26, all of the latches 24 being tilted so that all of the slides 16 remain in place beneath the receptacles 5, 6, 7, 8, 9, 10, 11, 12, and 14. Suppose that a five-cent purchase is made out of a dollar. When the proper lever 54 of the cash register is depressed, this lever will move the arm 71 by means of the finger 72, the arm 71 actuating the lever 70 and the arm 73, the latter depressing the pawl 75 which will depress the lever 76 and through the tappet 26 and the latch 24 effect a release of the slide 16 of the five-cent receptacle 5, so that the said slide will remain in place beneath the receptacle 5 and thus prevent the dropping of a nickel, the one-dollar plunger 36 being manipulated as before to secure the correct change. Suppose that a purchase larger than five-cents but requiring the holding back of a nickel is made. The amount purchased is rung up on the register and the appropriate lever 54 will actuate one of the bars 44, the bar 44 picking up the appropriate plate 45 which through the medium of one lever 65 will actuate the tappet 26 which is individual to the five-cent receptacle 5, and release the latch 24 of the five-cent receptacle, so that the slide will not be withdrawn. However, if a five-cent purchase is made out of a dime, then the slide 16 of the five cent receptacle 5 must be withdrawn to deliver a nickel to deliver a nickel in change. Under such circumstances, when the ten-cent plunger 33 is pressed, the rack bar 82 of the plunger 33, meshing into the pinion 81, will rotate the pinion, the projection 81^a of which will tilt the pawl 75 so that it will not engage and depress the tap-

pet 26 of the receptacle 5. The latch 24 of the receptacle 5 will remain engaged with the slide 16 of the receptacle 5 and the said slide will be withdrawn when the shaft 57 is actuated, thereby depositing a nickel in change. When the plunger 33 is released, the spring 77 will bring the pawl 75 back into place above the tappet.

When paper money is used, instead of coins, the separate bills may be placed in small receptacles which will pass out of the receptacles as readily as will the coins.

Having thus described the invention what is claimed is:

1. In a device of the class described, a case; bars extended transversely of the case and having limited movement on the case; plates through which the bars extend, the plates having a movement transversely of the bars, and independent of the bars; means for actuating each plate independently of the bars; means for actuating each bar to pick up certain of the plates; money receptacles; closures therefor; means for connecting the closures with the plates to withdraw the closures when the plates are actuated; and tender indicating mechanism for selectively rendering the connecting means inoperative. 80
2. In a device of the class described, a case; a support mounted to slide therein; a slidably movable tappet; means for upholding the tappet upon the support; a money receptacle; a closure for the money receptacle; means connected with the support for controlling the closure; said means being engageable by the tappet when the tappet is depressed; a latch pivoted to the support and engaging the tappet to hold the tappet depressed; a fixed member in the case with which the latch engages when the support is slid; a tender-indicator and a sale registering member; and means for connecting the tender-indicator and the sale registering member with the tappet to actuate the tappet at different times. 95
3. In a device of the class described, a money receptacle; a closure operating beneath the money receptacle; a support mounted to slide toward and away from the money receptacle; a latch pivoted on the support and adapted to engage the closure; a tappet mounted to slide upon the support and engaging the latch; a sale indicating member; a tender-indicating member; and means for connecting the sale indicating member and the tender-indicating member with the tappet to actuate the tappet at different times. 100
4. In a device of the class described; a case; a shaft journaled in the case; a support mounted to slide in the case; a shaft journaled in the support; a tappet mounted to slide in the shaft; a tender-indicating member; a sale registering member; means 115

- for connecting the sale registering member and the said tender-indicating member with the tappet to actuate the tappet at different times; a money receptacle; a closure for the money receptacle; a latch carried by the support and adapted to engage the closure, the latch being engageable by the tappet; and means for moving the support.
5. In a device of the class described, a case; a shaft journaled in the case; a support mounted to slide in the case; a shaft journaled in the support; a tappet mounted to slide in the shaft; a latch fulcrumed on the support and engaged with the tappet; a fixed member in the case with which the latch engages to hold the tappet depressed when the support is slid; means for actuating the tappet; a money receptacle; a closure for the money receptacle; and a latch on the support adapted to engage the closure; the last specified latch being engageable by the tappet when the tappet is depressed.
6. In a device of the class described, a case; a support mounted to slide therein; a shaft journaled in the support; a tappet mounted to slide in the shaft; a money receptacle; a closure for the money receptacle; means connected with the support for controlling the closure, said means being engageable by the tappet when the tappet is depressed; a latch pivoted to the support and engaging the tappet to hold the tappet depressed; a fixed member in the case with which the latch engages when the support is slid; a tender-indicating member and a sale registering member; and means for con-

necting the tender-indicating member and the sale registering member with the tappet to actuate the tappet at different times.

7. In a device of the class described, spaced coin controlling members; separate devices for actuating the coin controlling members; a movably supported member; a sale indicator connected with the movably supported member; a pawl pivotally supported by the movable member and engaging one coin controlling member; and means operatively connected with the actuating device of the other coin controlling member for moving the pawl out of engagement with the first specified coin controlling member.

8. In a device of the class described, spaced coin controlling members; separate devices for actuating the coin controlling members; a movably supported member; a sale indicator connected with the movably supported member; a pawl pivotally supported by the movable member and engaging one coin controlling member; a pinion journaled adjacent the pawl and provided with a projection adapted to engage the pawl to move the same out of engagement with said coin controlling member; and a rack bar meshing into the pinion and supported by the actuating device of the other coin controlling member.

In testimony that I claim the foregoing as my own, I have hereto affixed my signature in the presence of two witnesses.

JOHN G. WILLICH.
